UNITED STATES PATENT OFFICE

167,359

HOOD ORNAMENT FOR AN AUTOMOBILE

Henry T. King, Detroit, Mich., assignor to
Chrysler Corporation, Highland Park, Mich., a
corporation of Delaware

Application September 7, 1951, Serial No. 16,559

Term of patent 7 years

(Cl. D14—18)

To all whom it may concern:

Be it known that I, Henry T. King, a citizen of the United States, residing in the city of Detroit, county of Wayne, and State of Michigan, have invented a new, original, and ornamental Design for a Hood Ornament for an Automobile, of which the following is a specification, reference being had to the accompanying drawing, forming part thereof, in which:

Fig. 1 is a side elevational view of a hood ornament for an automobile showing my new design;

Fig. 2 is a top plan view thereof;

Fig. 3 is a front elevational view; and

Figs. 4 and 5 are cross sectional views taken on the lines 4—4 and 5—5 of Fig. 1.

The characteristic features of my design reside in the portions shown by means of solid lines in the drawing.

I claim:

The ornamental design for a hood ornament for an automobile, substantially as shown and described.

HENRY T. KING.
